UNITED STATES PATENT OFFICE

2,219,801

RESPIRATORY FILTER

Joseph B. Biederman, Cincinnati, Ohio

Application November 30, 1939, Serial No. 306,863

2 Claims. (Cl. 128—148)

The present invention relates to respiratory filters of the type adapted to be placed inside the nostrils of the patient, where they may retain a medicament which is inhaled by the user.

In the treatment of respiratory diseases, such as asthma, hay fever and similar ailments, it is desirable that the patient be provided with a filter and frequently an inhalant which is constantly available so as to filter and medicate the breath of each inhalation. For this purpose various masks and similar devices have been provided, but such nasal or facial masks are unsightly and the patient does not readily accustom himself to their use, especially in public places. For this reason the present invention is directed to a filter which may be inserted into the nostril where it is entirely concealed, thus relieving the user of all embarrassment, while at the same time giving him the full benefit of such use at all times. In view of the fact, however, that individual noses differ in size and the nostrils differ accordingly, it has heretofore been necessary to provide numerous sizes of such filters in order to meet the various demands. My present device adapts itself readily to noses of various sizes and therefore it becomes unnecessary for the dealer to carry an assortment of sizes of the device. The principal object is therefore to provide a respiratory filter of the type mentioned which adapts itself readily to noses of varying sizes.

Other objects of the invention will appear from the following detailed description thereof. In the drawing:

Figure 1 is a view looking upwardly into a nose provided with respiratory filters made in accordance with this invention.

Figure 2 is a perspective of the nasal filter as constructed in a preferred form.

Figure 3 is a perspective of a modified form of the device.

Figure 4 is a perspective of a still further modification of the device.

Figures 5 to 11 inclusive are plates of various sizes entering into the adjustability of my new filter.

Referring to the devices as illustrated in Figures 1 and 2, and Figures 5 to 11, the numerals 1 and 2 indicate two substantially semicircular end pieces entering into the construction of my new filter. Each of said end pieces is provided with inturned flanges 3, forming grooves which are adapted to receive the respective ends of a spring spacing plate 4. The end pieces 1 and 2, as well as the plate 4, are constructed of some non-cor-

rosive metal, such as silver, of suitable rigidity and in the case of the plate 4, of a certain springy quality. The inner sides of the end pieces between the grooved flanges 3 are provided with studs 5 which are adapted to engage in apertures 6 near the ends of plate 4, thus retaining the parts in assembly. The end members 1 and 2 are provided with fingers 7 which extend inwardly and substantially parallel with the plate 4 when the parts are in assembly. The fingers 7, co-operating with the members 1 and 2, are adapted to hold in the device a quantity of cotton or other suitable material 8 which is saturated with the desired medicament. Figures 5, 6, 7, 8, 9, 10 and 11 illustrate various sizes of plate 4, each being provided as shown with end apertures 6—6, any one of which plates may be used in connection with the end members 1 and 2, the parts being readily separated and reassembled with the desired plate 4 inserted.

In Figure 3 a modified form of the device is shown, wherein instead of the plates 4 of varying sizes, the end member 1 is provided with fingers 9, which are provided with grooves 10 and spaced perforations 11 and the end member 2 with fingers 12 which are provided with studs 13 adapted to engage in either of the perforations 11. The end members 1 and 2 will thus by reason of the telescoping engagement of their respective fingers be adapted to adjustments, adapting the device to nostrils of various sizes. In this form of the device the fingers also work to retain in the filter the filtering material such as lamb's wool which may be saturated with a suitable medicament. An alternate form of this device would employ compression springs instead of telescoping fingers to secure the end members together and to effect their adjustability.

In Figure 4 the end members 1 and 2, as well as the plate 4, are provided with grooves 14, 15, and 16 which are in alignment when the parts are assembled as described in connection with Figure 1. However, the end members may be permanently secured to the plate 4, if desired, as the adjustability is provided by means of a flap or valve 17 of thin rubber or other compressible material which is provided with a central opening, the rim of which fits into the grooves 14, 15 and 16 as shown in Figure 4. When the device so constructed is inserted in the nostril, the flap on valve 17 serves to close up all space surrounding the filter proper, thus adapting the construction to nostrils of various sizes.

From the foregoing description, the nature, construction and use of my new respiratory filter

will be apparent to those skilled in the art to which the same appertains. In either of the forms illustrated it is apparent that the device is readily adaptable to nostrils of various sizes and that when inserted it is arranged adequately to support a filtering material and/or a properly medicated wad of lamb's wool or other similar material. It is obvious of course that numerous changes in details of construction may be made without departing from the spirit of the disclosure of my invention as above set forth; for instance as shown in Figures 8 and 11, the plates 4 may be provided with a plurality of openings 6, so that a single plate may serve for a number or all of the adjustments; in the form shown in Figure 4, the device may be provided with varying sizes of rubber flaps or valves and a single size framework to fit therein, thus adapting it to various sizes of nostrils, or a single size rubber flap 20 may be provided with a plurality of elements as shown in Figures 1 and 2 adapted to fit therein. The specific arrangement of the grooves and perforations in Figure 3 may also be modified as well

as the means for securing the parts together as shown in Figure 2. All of such changes and modifications are within the spirit of the above disclosure and within the purview of the appended claims.

Having thus fully described my invention what I claim as new and desire to secure by Letters Patent is:

1. A respiratory filter comprising end members adapted to fit into the nostril of a user, grooved flanges on each of said end members, an intermediate plate, and means whereby the end of said plate may be secured removably in the grooves of said flanges.

2. A respiratory filter comprising end members adapted to fit into the nostril of a user, fingers carried by said end members and adapted to secure a pad therein, grooved flanges on each of said end members, an intermediate plate, and means whereby the end of said plate may be secured removably in the grooves of said flanges.

JOSEPH B. BIEDERMAN.
